Patented Dec. 30, 1913.

UNITED STATES PATENT OFFICE.

CHARLES W. LANG, OF UTICA, NEW YORK, ASSIGNOR TO SAVAGE ARMS COMPANY,
OF UTICA, NEW YORK, A CORPORATION OF NEW YORK.

FIREARM.

1,082,961.

Specification of Letters Patent. Patented Dec. 30, 1913.

Application filed October 15, 1912. Serial No. 725,952.

To all whom it may concern:

Be it known that I, CHARLES W. LANG, a citizen of the United States, residing at Utica, in the county of Oneida and State 5 of New York, have invented certain new and useful Improvements in Firearms, of which the following is a specification.

This invention relates particularly to safety locking devices for firearms.

10 It has for its object to provide a fire-arm with a simple and reliable locking means, this object having been carried out in the specific form of the invention shown and described herein with reference to the sear-tripping or releasing means of an arm of the kind illustrated, for instance, in the patent to Searle, No. 936,369 wherein is employed a device for locking the breech-bolt and the firing mechanism, which device I 15 20 utilize as a detent in obstructing the tripping or releasing movement of the sear-tripping or releasing mechanism.

In the accompanying drawings, Figure 1 is a side elevation of the improved arm, 25 somewhat enlarged and partly in section; Fig. 2 is a view of the arm partly in plan and partly in section with the breech-structure removed, the plane of the section being coincident with the horizontal plane of the 30 obstructor *r*; Fig. 3 is a sectional view on the line *x*—*x* of Fig. 2; and, Fig. 4 illustrates a detail.

The frame *a*; the barrel *b*; the breech-bolt *c* having the removable plug *d* forming 35 therewith a breech-structure which slides on the frame back and forth under the counter influences of the explosion-pressure and a spring (not shown); the firing-mechanism arranged in the plug *d* and including the 40 cocking-lever *e*, a firing-pin connected therewith and a sear *f* for locking the firing-pin and lever *e* in cocked position; the sear-releasing or tripping means including the trigger *g* arranged to slide back and forth 45 in the frame and a sear actuator *h* movable, by being pivoted, in the trigger crosswise of the path of movement of the trigger for a purpose which will be clear upon reference 50 to the Searle patent aforesaid; and the locking device or detent consisting of a spindle *i* journaled in the frame and having a handle *j* and being adapted when turned to the dotted line position in Fig. 1 both to leave the breech mechanism free to move longitudinally and the cocking-lever *e* free to 55

move against the firing-pin (because at that time a lug *k* of the cocking-lever coincides with a cross-cut slot *l* in the spindle *i*) and being further adapted, when turned into the full line position in Fig. 1, to be received 60 by one or the other of notches (not shown) in the breech-bolt, to lock the breech mechanism against longitudinal movement and to oppose firing movement of the cocking lever (because its slot *l* is not in registry with the lug *k*, which then impinges against the spindle) are or may be substantially the same as in the said patent to Searle. In the inner face of the said wall of frame *a* to which the sear actuator *h* is adjacent is formed a 65 horizontal guideway *m*, the same being a groove extending from the spindle *i* forward to a point beside the actuator *h*, excepting where the partition *n* separates the magazine chamber in the grip portion *o* of the arm from the recess *p* partly receiving the sear releasing means, where (through said partition) said way takes the form of a 70 aperture *q*. In this way slides the sear-releasing-mechanism-movement-obstructor *r* 75 80 in the form of a rod or bar which is housed within the groove portion of the way and is kept in place partly by fitting the aperture *q*, which it penetrates, and partly by the housing *s* for a spring *t* which bears against 85 an angular face *u* of the spindle *i* of the detent, serving to hold the latter at either of its limits of movement against the shoulders *v*. At its forward end the rod *r* has an inwardly projecting stud or pin *w* entering a 90 cross-cut slot *x* in the actuator *h*, the other end of the rod being a reduced portion or pin *y*. The spindle *i* has a hole *z* radially bored therein in such relation that said hole will register with the pin *y* when the detent 95 is moved to the dotted line position in Fig. 1. The slot and pin connection *w*—*x* between the rod *r* and actuator *h* obviously allows free movement of the latter crosswise 100 of the path of movement of the sear-tripping mechanism, although movement of said mechanism back and forth in tripping the sear will by said connector be transmitted to the rod *r*.

In the position shown in the drawings, 105 where the locking device or detent is obstructing the firing-movement of the cocking lever and locking the breech-mechanism against longitudinal movement, the sear tripping or releasing mechanism cannot be 110

5 moved because the obstructor opposes movement of said mechanism and has its own movement opposed by said detent; on moving the detent, however, to the dotted line position, so that the cocking-lever may move on the tripping of the sear, since hole α now registers with pin γ the sear tripping mechanism may be moved back to actuate the sear.

10 Having thus fully described my invention, what I claim as new and desire to secure by Letters Patent is:—

15 1. In combination with a gun having a frame, a firing mechanism, and a normally retracted releasing means for the firing mechanism movable in the frame, a movement-obstructor for the releasing means slidable in the frame, and a locking device for the firing mechanism controlling the sliding movement of said movement obstructor, substantially as described.

20 2. In combination with a gun having a frame, a cockable firing mechanism, and mechanism, including releasing means for the firing mechanism, movable thrustwise in the frame, a locking device common to both said mechanisms, substantially as described.

25 3. In combination with a gun having a frame, a firing mechanism, and a normally retracted releasing means for the firing mechanism movable in the frame and in-

cluding a firing mechanism actuator movable crosswise of the path of movement of said means, means for locking the releasing means against movement including an obstructor movable with said releasing means and having lost motion connection with the actuator, substantially as described.

4. In combination, with a gun having a frame, a cockable firing-mechanism including a sear, and a normally retracted releasing means for the sear movable in the frame and including a sear-actuator movable crosswise of the path of movement of said means, means for locking the releasing means against movement including an obstructor movable with said releasing means and having a slot and pin connection with the actuator, substantially as described.

45 5. In combination, with a gun having moving parts to be locked, locking devices for said parts respectively controlling the latter and one controlling the other, the controlling device being rotary and the controlled device thrustwise movable, substantially as described.

50 In testimony whereof I affix my signature in presence of two witnesses.

CHARLES W. LANG.
